SEWING MACHINE LUBRICATING MEANS

Bernard C. Ellersick, St. Louis, Mo., assignor to
The Singer Manufacturing Company, Elizabeth,
N. J., a corporation of New Jersey

Application January 16, 1941, Serial No. 374,615

3 Claims. (Cl. 112—256)

This invention relates to sewing machines and more particularly to means for lubricating the mechanism within the hollow head.

When sewing machines of the lock-stitch type are operated at high speeds of about 80 revolutions a second, lubrication of the bearing surfaces of the crank for the needle-bar and take-up links is difficult. Due to the high speed, if oil is supplied from a point exteriorly of the bearing the centrifugal force created by the high speed throws the oil off before it reaches the bearing surfaces. On the other hand, if oil is supplied through the crank to the bearing surface, it is difficult to meter the oil with the result that either not enough or too much oil is supplied at the various speeds.

Oiling the mechanism of sewing machines presents many problems for the machine may be called upon to operate at 100 R. P. M. for a few seconds, then jumped to 5000 R. P. M. and in finishing the seam the speed may be reduced to 500 R. P. M. On other work the same machine may be accelerated from 0 to 5000 R. P. M. in less than a second, and on heavy work the machine may not be operated over 2000 R. P. M. at any time. Under these varying conditions the correct amount of oil must be supplied at all times. Insufficient oil will, of course, cause rapid disintegration of the parts and an oversupply will damage the work. It is the object of this invention to deliver a small quantity of oil directly to the bearing surface of the crank within the hollow head each time the crank is rotated, thereby applying a film of oil directly to the crank and eliminating the uncertainty of the oil not reaching the bearing surface.

With the above and other objects in view, as will hereinafter appear, the invention comprises the devices, combinations, and arrangements of parts hereinafter set forth and illustrated in the accompanying drawing of a preferred embodiment of the invention, from which the several features of the invention and the advantages attained thereby will be readily understood by those skilled in the art.

Figure 1 is a front elevation of the hollow head of a sewing machine embodying my invention, the face-plate being removed to disclose the parts within the head.

Figure 2 is an enlarged detailed view of the crank and link connections within the hollow head.

Figure 3 is a side elevation and Figure 4 is a section of the operative connection between the needle-bar link and the crank.

Figure 5 is a view similar to Figure 4, showing a construction in which the crank-pin is directly wiped by the wick.

In the embodiment of this invention selected for illustration, 10 represents the usual hollow head in which is journaled a rotary actuating shaft 11, and fixed to the end extending into the hollow head is a crank-disk 12 carrying the crank-pin 13 which actuates the link 14 of the needle-thread take-up mechanism 15. Carried by the crank-pin 13 is a second crank-pin 16 which is embraced by the strap 18 at one end of a pitman 17, the other end of the pitman being operatively connected to the needle-bar 19 which is journaled in the bearings 20 and carries an eye-pointed needle 21. Interposed between each of the crank-pins 13 and 16 and the strap 18 of the pitman 17 and the strap 14' of the link 14 are a series of small rollers or needle-bearings 22 which serve to reduce friction between these elements and the crank-pins. Journaled in bearings 23 in the hollow head is the usual presser-bar 24 which is constantly urged downwardly by the spring 25. To the lower end of the presser-bar 24 there is secured the usual presser-foot 26 which cooperates with the feed-dog (not shown) for advancing the material. Fixed in the upper part of the head of the machine is a supporting plate 27 provided with depending tubes 28 which carry wicks 29, the function of which will be hereinafter described. For a complete description of the sewing machine, and the parts above described, reference may be had to the patent to R. Kaier, No. 2,206,285, dated July 2, 1940.

To adequately lubricate the bearing surface between the rollers 22 and the strap 18 of the pitman 17, I have provided the strap 18 with an elongated peripheral opening 30 which extends through the upper portion of the strap of the pitman so as to expose the rollers 22 (Figs. 3 and 4). As shown, the wicking 29 is bent back upon itself in the tube 28 to form a loop and this loop extends downwardly to a point so that it will engage the rollers 22 on each rotation of the crank. A thin film of lubricant is thus applied directly to the bearing surface and it finds its way underneath the strap before it is thrown off by the centrifugal force created by the operation of the parts. It will be understood that the wicks are constantly supplied with lubricant during the operation of the machine, the same means being used as that shown in the Kaier patent referred to above.

55 It will be observed that the portion of the

strap 18 in which the opening is located is thickened to add strength to the two ribs 18' which are located on each side of the opening (Figs. 3 and 4).

It will also be understood that the bearing surface between the strap 14' of the link 14 and the crank 13 is lubricated in the same way as that used for lubricating the strap 18. The rollers 22 which are interposed between the crank-pins 13, 16 and the straps 14' and 18 are for the purpose of reducing friction and, so far as this invention is concerned, the rollers 22 may be considered as part of the crank-pins which they encase.

Having thus set forth the nature of the invention, what I claim herein is:

1. In a sewing machine having an endwise reciprocating needle, a rotary crank-shaft, an anti-friction bearing on the crank of said shaft, a needle-driving connecting rod having a strap embracing said anti-friction bearing, the improvement which consists of the provision of a peripherally elongated opening in the strap of said connecting rod exposing said needle-bearing, and a lubricant conducting wick arranged to be wiped by said anti-friction bearing through the peripher-

ally elongated opening in said connecting rod strap.

2. In a sewing machine having a hollow head, a rotary crank within said head, a link having a strap at one end which embraces said crank, the other end of the link being connected to one of the elements of the stitch-forming mechanism, said strap having a peripherally elongated groove which extends therethrough, a stationary wick holder depending from the top of the hollow head, and a wick threaded into said holder so that it depends therefrom in a loop which enters said groove and engages said crank.

3. In a sewing machine having a hollow head, a rotary crank within said head, the crank being embraced by the crank-strap of a crank driven element and having a bearing surface therebetween, the improvement which consists in the provision of a stationary lubricant conducting wick arranged to be wiped by said bearing surface and the provision of an opening in said strap large enough to expose a portion of said bearing surface to the wiping action of said wick.
